(57) **CLAIM**

The ornamental design for a core for a glass lite, as shown and described.

DESCRIPTION

FIG. 1 is a front elevational view of our design, the side opposite being a mirror image;

FIG. 2 is a front elevational view of a second embodiment of our design, the side opposite being a mirror image;

FIG. 3 is a front elevational view of a third embodiment of our design, the side opposite being a mirror image;

FIG. 4 is a front elevational view of a fourth embodiment of our design, the side opposite being a mirror image;

FIG. 5 is a front elevational view of a fifth embodiment of our design, the side opposite being a mirror image;

FIG. 6 is a front elevational view of a sixth embodiment of our design, the side opposite being a mirror image; and,

FIG. 7 is a front elevational view of a seventh embodiment of our design, the side opposite being a mirror image.
